CORNER LOCK FOR BEDSTEADS

Henry Richardson, Chicago, Ill.

Application February 26, 1931, Serial No. 518,329

8 Claims. (Cl. 5—296)

This invention relates to corner joints or locks for bedsteads, and its primary object is to provide a simple and improved corner joint for bedsteads having side rails comprising a vertically disposed bar suitable for exposure as the side of a bedstead, and in which an end edge of said bar is wedged against a bed end, preferably flush with the surface of the latter, by wedging means which may be entirely concealed from view when a bedstead is in service.

The present corner joint, in its preferred forms as herein shown and described, is composed solely of a pair of plates each having a portion formed with an inclined rail-locking edge, one 15 of said plates being secured to and projecting from a bed corner post, and the other of said plates being secured to the inner side of the vertically disposed bar of a side rail.

The bed corner construction herein shown and 20 described is a simplification of and improvement on the corner joint disclosed in my Letters Patent No. 1,898,392, dated February 21, 1933, in which a vertical side bar and rail wedging plate secured thereto, are both located on 25 one side of a vertically disposed bracket plate, and a headed stud on said wedging plate cooperates with an inclined edge of said bracket plate and another inclined edge of the latter plate is engaged with the said wedging plate. In the 30 present construction, the above mentioned headed stud and one of the said inclined edges are eliminated, a vertical side bar and wedging plate secured thereto being respectively disposed on opposite sides of a bracket plate.

In the preferred forms of the present corner joint herein shown an end edge of a wooden side bar is wedged against a bed end, said wedging being maintained against loss by shrinkage in 35 the length of said bar, by means including a co-operative movement of said bar and a wedging plate thereon. The preferred form of bracket for a wooden bed end consists simply of a straight vertically disposed plate, an end extension of which is secured to said bed end in the manner 40 shown by the drawings. An L-shaped bracket may be used on a wooden bed end but is neither necessary nor desirable, this form of bracket being more suitable for metal bed ends having either square or round corner posts and is 45 preferably used for such ends.

Other objects and attendant advantages of the invention will be apparent to persons familiar with devices of this character from the following detailed description, taken in connection 50 with the accompanying drawings, wherein I have

illustrated two slightly different embodiments of the principle of the invention, and in which—

Fig. 1 is an inner side elevation of a corner post and end portion of a wooden bar or side rail of a bedstead showing my improved lock applied thereto and in assembled relation.

Fig. 2 is a similar view but showing the co-operating parts of the locking device separated.

Fig. 3 is a vertical transverse section taken on the line 3—3 of Fig. 1.

Fig. 4 is a top plan view of Fig. 2, with the corner post and post bracket in horizontal section on the line 4—4 of Fig. 2; and

Figs. 5, 6, 7 and 8 are views corresponding with Figs. 1, 2, 3 and 4, respectively, showing reversed 70 positions of the cooperating wedging elements on the bracket side plate and side rail wedging plate.

Fig. 9 is a view similar to Figs. 1 and 5, showing an application of the invention to a round tu- 75 bular metal corner post, the latter appearing in section on the line 9—9 of Fig. 11.

Fig. 10 is a vertical transverse section taken on the line 10—10 of Fig. 9.

Fig. 11 is a top plan view, in section through 80 the corner post on line 11—11 of Fig. 9, and showing the cooperating locking parts separated.

Referring first to Figs. 1 to 4 of the drawings, 10 designates a rectangular wooden corner post or the corresponding portion of a wooden bed 85 end, and 11 the deep wooden side rail equipped, as usual, on the inner side of its lower edge with a ledge 12, which constitutes the support for a bed spring or slats carrying said spring. The inner face of the post 10, as shown in Fig. 4, is 90 vertically mortised to receive a flat vertically projecting bracket side plate 13, which has a longitudinally disposed end extension 13' firmly secured to said post by pins 14 entered into said post crosswise of the latter, the inner end or 95 ends of said pins 14 being preferably covered and concealed by packings 15 of plastic wood or other filler material.

A portion of the bracket plate 13 is extruded 100 to form on its inner side a wedging member or rib 16, having a continuous inner edge 16' which is downwardly inclined toward the post 10 for a purpose later explained. This extruded rib 16 is readily formed out of the metal of the bracket plate 13 by a suitably shaped die or punch and is 105 of substantial length, as shown.

To the inner side of the wooden side rail 11 is attached a metal member designated as a whole by 17 and consisting of a flat rail locking and wedging plate 18 offset from the inner side of 110

the side rail 11 to provide a recess for the side plate 13 and having an end extension 19 adapted to be securely attached to the side rail by a plurality of screws 20 of such length that, when 5 screwed fully home, they will not pierce the outer or finished surface of the side rail, as clearly shown in Fig. 4. The rail locking member 18 is formed with a downwardly extending portion 21 having an inclined edge 21' possessing the same 10 inclination as the inner edge 16' of the rib 16. By reference to Fig. 1 it will be observed that the vertical edge of the metal member 17 next to the bed end lies slightly inwardly of the vertical end edge of the side rail, the purpose of this being 15 to prevent the said edge of this member, when the latter is attached to the wooden side rail, interfering with the longitudinal movement of the side rail by means of which the wedging of the vertical end edge of said rail is constantly maintained. 20

By reference to Fig. 4 it will be observed that the distance of the locking and wedging plate 18 of the metal member 17 from the inner surface of the side rail 11 is substantially equal to 25 the thickness of the bracket plate 13, being such as will afford an easy sliding fit of the bracket plate 13 between the said plate 18 and said side rail 11. The parts may be assembled by a direct downward movement of the side rail, the top 30 edge of the bracket plate 13 being passed into the recess between said plate 18 and side rail 11 and the rail lowered until the sliding contact of the inclined edge 21' of the downwardly extending portion 21 with the inclined edge 16' of the rib 16 tightly wedges the vertical end edge of the wooden side rail 11 against the opposed face of the wooden bed post 10, said sliding contact cooperating with a further movement of the wooden side rail 11 and wedging plate 18 thereon to maintain 35 said wedging against loss by shrinkage in the length of said side rail. This prevents any angular looseness or play in a vertical plane between the side rail and the post; and with the bracket plate held between the side rail and the locking and wedging plate, manifestly, the side rail cannot swing horizontally relatively to the bed end or become laterally displaced in either 40 direction from the bracket plate.

By reference to Figs. 5 to 8 inclusive, it will 50 be seen that the only structural differences therein shown over the structure of Figs. 1 to 4 inclusive, is a reversal of location of the wedging rib 16 and its cooperating downwardly extending portion 21 with relation to the bracket and rail plates. In this case the rail locking and wedging plate 18^a of the metal plate 17^a on the wooden side rail is formed on its outer side with an extruded rib 16^a having a continuous rear edge 16'' downwardly inclined towards the post 10, said rib being directed toward the side rail 11, as seen in Fig. 8, and the bracket plate 13^a is formed to provide the downwardly extending portion 21^a having a continuous straight flat inclined edge 21'' that cooperates with the inclined edge 16'' of the lug 16^a. 60

The manner of assembling the parts of the construction shown by Figs. 5 to 8 inclusive is manifestly the same as that described in connection with Figs. 1 to 4 inclusive. In the last-mentioned 70 structure the downwardly extending portion 21 being on the metal plate 17 secured to the wooden side rail, the bracket plate 13 offers a stronger resistance to disrupting strains and may be of lighter metal than when said downwardly extending portion is formed out of the bracket plate, 75

as in Figs. 5 to 8, and the structure shown by Figs. 1 to 4 has also some advantage in the better visibility of the parts when the side rail is connected to the bed end.

An important object of the present invention is to provide a simple and efficient joint for a bedstead in which the bed ends are of metal and the side rails have a deep vertically disposed bar adapted to furnish said bedstead with sides suitable for exposure when in service, and which may be equally as attractive in appearance as the customary sides of an all wooden bedstead. To efficiently wedge an end edge of the vertically disposed bar of a side rail against and in direct contact with the metal surface of a round tubular corner post, it is necessary for the latter to be formed with a flat surface to accommodate the said edge, and as shown by the drawings, the said surface has been provided by flattening a portion of said round metal post so that a recess is formed in the latter in such a manner that the punching of the two holes necessary to secure the bracket to said post and the said flattening may be done by the same operation. By reference to Fig. 9 it will be observed that the flattened surface of the 100 post is of greater length than the width of the contacting end of the bar 11, in order to permit the engagement and disengagement of the cooperating parts of the corner fastening. A flat surface on a round tubular metal corner post is believed to be a novel feature in bed corner construction. A side rail may be entered into the recess formed by said flattening without being wedged against the surface of the recess, the use of the latter as a seat for the post-engaging portion of a bracket on the bed end being alone a valuable advantage of said recess. 105

In Figs. 9, 10 and 11 I have illustrated an application of the corner joint, as shown in Figs. 1 to 4 inclusive, to a tubular metal corner post, the latter 115 being formed with a flattened portion for the attachment of the bracket and the abutment of the vertical end edge of the side rail. By means of a suitable die and punch, which may be combined in one, a portion of the wall of the tubular post 22 120 is indented and flattened, as shown at 23, and holes are punched therein for the reception of rivets 24 by which the attaching limb 25 of an angle bracket is strongly secured to the post. The other limb 26 of the angle bracket projects to form 125 a bracket side plate identical functionally with the bracket side plate 13 of Fig. 1, this bracket side plate being formed with the extruded rib 16 for cooperation with the downwardly extending portion 21 of the wedging plate 18 that is secured 130 to the inner side of the deep wooden side rail 11, and said rib and downwardly extending portion cooperating to wedge the vertical end edge of the side rail against the flattened portion 23 of the post. Of course, the cooperating rib 16 and downwardly extending portion 21 may be reversed as to location in this construction, as is illustrated in 135 Figs. 5 to 8 inclusive; but such reversal being obvious, I have not deemed it necessary to further illustrate the same. The manner of assembling 140 is obviously the same as that above described in connection with the previous figures.

The cooperating inclined wedging means of the several forms of the invention illustrated in the drawings have been described and are shown as 145 continuous inclined surfaces, but manifestly two or more separated surfaces tangent to an inclined line would be the equivalent, and may be employed within the scope of the invention. Other minor changes falling within the spirit and purview of 150

- the appended claims may also be made in the constructions herein shown and described.
- A commercially valuable feature of the present invention is that it supplies, at a very low cost of material and labor, a strong, practical and highly efficient corner joint well suited in every respect for that type of beds having deep wooden or imitation wood side rails designed to fully conceal all metal parts of the corner joint or lock.
- 10 I claim:
1. A bedstead corner fastening consisting solely of a bracket side plate having an extension adapted for attachment to a bed post, a wooden side bar disposed on the outer side of the side plate, and a second plate secured to the inner side of said bar and having a portion thereof adjacent the inner surface of the side plate, one of said plates being formed with a downwardly extending portion having an edge downwardly inclined toward the bed post, the other plate having an offset portion, a movement of the bar and said second plate cooperating with an engagement of the offset portion against the said inclined edge to effect and maintain a wedging of an end edge 25 of said bar against the bed post.
  2. A bed corner fastening consisting solely of a bracket side plate having an extension adapted for attachment to a bed post, a wooden side bar disposed on the outer side of the side plate, and a second plate secured to the inner side of said bar and having a portion thereof adjacent the inner surface of the side plate, one of said plates being formed with a downwardly extending portion having an edge downwardly inclined toward the bed post, the other plate having an offset portion, the offset portion having an inclined edge engaged with the inclined edge of said downwardly extending portion and cooperating with a movement of the bar and said second plate to effect 40 and maintain a wedging of an end edge of the bar against the bed post.
  3. A corner joint for bedsteads comprising a bed end having an arcuated hollow metal corner post, a bracket comprising a post flange adapted to be attached to said post and a side flange at one side of said post flange and at right angles thereto, and a side bar, a portion of the said post being flattened to constitute a recess adapted to accommodate a portion of said post flange seated against the surface of said recess, and cooperating rail locking means on the bracket member and side bar connecting the last-named parts to one another.
  4. A corner joint for bedsteads comprising a bed end having an arcuated hollow metal corner post, a bracket comprising a side plate having an extension thereof secured to said post and a vertically disposed side bar, a portion of the said post being flattened to provide a recess for an end edge and end portion of said bar entered therein, and cooperating rail locking means on the side plate and side bar connecting said last-named parts to one another.
  5. In a corner joint for bedsteads, the combination of a round hollow metal corner post having an indented flat surface, a bracket secured to and projecting from said post to provide a vertically disposed side plate, a side rail comprising a deep
- vertically disposed bar, and rail wedging means on said bar and side plate cooperating to wedge an end edge of said bar against and in contact with the indented flat surface of said round corner post, said flat surface being of greater length than the width of the contacting end of said bar.
6. In a corner joint for bedsteads, the combination of a round hollow metal bed corner post having an indented flat surface, a side rail comprising a deep vertically disposed bar, and cooperating coupling plates attached respectively to said corner post and the inner side of said bar; said coupling plates being provided with members having inclined surfaces brought into sliding contact with each other during the coupling operation, said inclined surfaces cooperating to tightly wedge an end edge of said bar against and in contact with the indented flat surface of said corner post, said flat surface being of greater length than the width of the contacting end of said bar.
7. In a corner joint for bedsteads, the combination of a round hollow metal bed corner post having an indented flat surface, a bracket secured to and projecting from said post to constitute a side plate, a side rail comprising a deep vertically disposed bar equipped with a wedging plate spaced from said bar to provide a passageway for said side plate between said wedging plate and bar, each of said plates being provided with rail wedging means adapted to be brought into sliding engagement with one another by the entrance of said side plate within said passageway, the construction being such that said wedging plate has a freedom of movement toward said corner post whereby the engagement of said inclined wedging means wedges an end edge of said vertically disposed bar against and in contact with the indented flat surface of said corner post, said flat surface being of greater length than the width of the contacting end of said bar.
8. A bed corner joint, comprising a bed end, a bracket side plate secured to and projecting from the bed end to constitute a side plate, a wooden side bar disposed on the outer side of the side plate, and a wedging plate directly attached to said bar and having an end portion thereof lying on the inner side of the side plate and spaced from the wooden bar a distance substantially equal to the thickness of the bracket side plate, one of said plates being formed with a downwardly extending portion having an inclined edge, the other plate being provided with a laterally projecting member which, by a sliding engagement with said inclined edge, wedges an end edge of said bar against the bed end, the length and position of the wedging plate being such that the end adjacent the bed end is free of all contacts in a direction longitudinally of the bed, said sliding engagement also cooperating with a movement of the said wedging plate and bar to provide compensation for shrinkage in the length of said side bar, whereby said wedging action is constantly maintained, and relative lateral angular displacement of the side rail and bed end is prevented.

HENRY RICHARDSON.
